UNITED STATES PATENT OFFICE.

FRANK BERENSTEIN, OF CHELSEA, MASSACHUSETTS.

FRiction-PLUG RUBBER HEEL

1,173,088.

Specification of Letters Patent. Patented Feb. 22, 1916.

Application filed November 11, 1915. Serial No. 60,951.

To all whom it may concern:

Be it known that I, FRANK BERENSTEIN, a citizen of the United States, resident of Chelsea, in the county of Suffolk and State 5 of Massachusetts, have made a certain new and useful Invention in Friction-Plug Rubber Heels; and I declare the following to be a full, clear, and exact description of the same, such as will enable others skilled in 10 the art to which it appertains to make and use the invention, reference being had to the accompanying drawings, and to letters or figures of reference marked thereon, which form a part of this specification.

15 Figure 1 is a bottom plan view of the invention. Fig. 2 is a section on the line 2—2 Fig. 1. Fig. 3 is a detail view showing the nail, the post and the washer in perspective.

20 The invention has relation to rubber heels, and particularly to friction plugs for such heels and other tread members, having for its object certain improvements upon the Patent No. 1,129,672, of S. J. Harris, the

25 object being to accomplish a better union between the bracing means or post and the canvas plug and to avoid liability of the post scratching polished floors.

The invention consists in the novel construction and combinations of parts, as hereinafter set forth.

In the accompanying drawings, illustrating the invention, the numeral 2 designates the wear lift of the rubber heel, and 3 the 35 upper lift of said heel.

The plug in the present case consists of a back plate 4, usually of circular form and of metal, of the same or a little less in diameter than that of the plug proper 5, which is 40 wound from a strip of frictionized canvas or other suitable rubber-coated material and is provided with a central perforation 5'.

6 is the post, located within the perforation of the plug proper and formed of a 45 material different from that of the back plate, usually of hard rubber, although indurated fiber or hot pressed paper or the like may be used, the object being to provide a post of material to which the rubber-coated 50 material of the plug proper will adhere or be united more closely in the manufacture of

the heel, to form a unitary article, and at the same time to avoid liability of the post scratching or marring polished floors, said post having still the function of holding the 55 plug in position in the heel, and the greater adherence of the rubber-coated material of the plug proper to the post being needed, inasmuch as the special post of said patent, for holding the plug proper in position, is 60 done away with. And inasmuch as the post is formed of a material different from that of the back plate, it is necessary to make the post separate from the back plate.

The fastening nail 7 has its head engaged 65 within the perforation of the hollow post and its shank engaged with the center perforation of the metal back plate. The perforation of the back plate is of smaller size than that of the hollow post, and is provided 70 with a marginal portion overlying the top of the perforation of the post and adapted to be engaged by and back up the head of said nail.

I claim:

75 In a rubber heel having a recess, a hollow cylindrical plug of rubber-coated fabric material located within and cemented to the side wall of said recess, a metal back plate extending across and having bracing engagement with the top of said plug, and a central hollow post fitting within the perforation of said plug and separate from said back plate, said post being of a non-metallic material 80 comparatively soft with relation to said back 85 plate and to which the rubber-coated material of the plug proper will closely adhere, the interior diameter of said post being comparatively large to receive the head of a fastening device, and said back plate having 90 a central perforation of small size to receive the shank of said device, the marginal portion of said back plate surrounding the central perforation thereof extending across the 95 perforation of the post and acting as a back- ing for the head of said device.

In testimony whereof I affix my signature, in presence of two witnesses.

FRANK BERENSTEIN.

Witnesses:
